UNITED STATES PATENT OFFICE

2,648,500

RAIL FASTENING DEVICE

George S. Vickroy, Johnstown, Pa., assignor to
 United States Steel Corporation, a corporation
 of New Jersey

Application September 1, 1950, Serial No. 182,753

2 Claims. (Cl. 238—349)

1

This invention relates to a rail fastening device and more particularly to a rail fastening device having a spring clip and a wedge for holding the clip in position. Wedges have been used in conjunction with clips prior to my invention but have not been satisfactory for various reasons. They may be difficult to insert or remove and in some instances they tend to work out of position due to the vibration of the rail.

It is therefore an object of my invention to provide a rail fastening device utilizing a wedge for holding a spring clip in position in which the wedge is locked in place.

This and other objects will be more apparent after referring to the following specification and attached drawings, in which:

Figure 1 is a top plan view of the device in position on a rail; and

Figure 2 is a sectional view taken on the line II—II of Figure 1.

Referring more particularly to the drawings, the reference numeral 2 indicates a tie plate which is mounted on the tie in the usual manner and which is provided with the usual rail seating portion 4 for receiving the flange 6 of a rail. An inverted U-shaped member 8 is welded to the base plate 2 on each side of the rail between the seat portion and the edge of the plate. A spring clip 10 passes through opening 12 in the U-shaped member 8 with one end bearing on the tie plate 2 and the other end bearing on the top surface 14 of the rail base. The upper surface of the spring clip 10 is longitudinally convex and is provided with a portion 16 in the opening 12 which is arranged at a steeper angle than the top surface 14 of the rail base. A locking key 18 is provided in the opening 12 between the clip 10 and the underside 20 of the U-shaped member 8. The locking key 18 has an upwardly extending lug 22 on the end thereof adjacent the rail, which lug prevents outward movement of the key. The locking key 18 has a bearing face 24 on its lower surface which engages surface 16 of the spring clip 10. The key 18 has a substantially flat portion 26 which engages the underside 20 of the U-shaped member and has a cut-out portion 28 on the outer end of the key.

In assembling the device the spring clip 10 is first placed in position in the opening 12. The wedge 18 is then inserted from the outside of the inverted U-shaped member 8 with the lug 22 being sprung into locking position by the clip 10 after it passes member 8. Due to the radius bend in the spring clip being approximately underneath the edge of the inverted U-shaped member 8, the

2

deflection of the spring clip 10 is minimized by the insertion of the locking key. Engagement of the lug 22 with the side of the U-shaped member 8 prevents outward movement of the key. The compression in the spring clip 10 forces the key 18 upwardly, thus locking the spring clip 10 in the position shown. Engagement of the surfaces 16 and 24 prevent outward movement of the clip 10 and also prevents inward movement of the key 18.

10 When it is desired to remove the key 18, the outer end is raised upwardly with a bar or other device and then knocked outwardly. The cut-out portion 28 facilitates this upward movement of the key 18.

15 While one embodiment of my invention has been shown and described, it will be apparent that other adaptations and modifications may be made without departing from the scope of the following claims.

20 I claim:

1. A rail fastening device comprising a tie plate having a seat portion for the base of the rail, a member secured to said tie plate at a point intermediate the seat portion and the edge of the plate, said member having an opening therethrough with the top surface thereof being spaced from the top of said tie plate, an elongated spring clip extending through said opening with one end of said clip bearing against the top of the rail flange and the other end bearing against the top of the tie plate, the upper surface of said clip being longitudinally convex, a portion of said clip in said opening being arranged at a steeper angle than the top surface of the flange of the rail, 25 a bend in said clip within said opening, and a locking key in said opening between said clip and said top surface, said locking key having a portion on its upper surface engaging said member to prevent outward movement of the key away from said rail, and a shoulder on its lower surface engaging the bend in said spring clip to prevent outward movement thereof.

2. A rail fastening device comprising a tie plate having a seat portion for the base of the rail, an inverted substantially U-shaped member secured to said tie plate at a point intermediate the seat portion and the edge of the plate, an elongated spring clip extending through said inverted U-shaped member with one end of said clip bearing against the top of the rail flange and the other end bearing against the top of the tie plate, the upper surface of said clip being longitudinally convex, a portion of said clip passing through said U-shaped member being arranged at a steeper angle than the top surface of the flange of the rail, a

locking key between said clip and the underside of said U-shaped member, an upwardly extending lug on the side of said key adjacent the rail for engaging the side of said member to prevent outward movement of the key away from said rail, said locking key having a portion on its lower surface engaging the spring clip to prevent outward movement thereof, a substantially flat portion on the top of said key engaging the underside of said U-shaped member, and a cut-out portion

5
10

on the end of said key opposite said lug and beneath the underside of said U-shaped member to permit downward movement of said lug.

GEORGE S. VICKROY.
